UNITED STATES PATENT OFFICE.

ALBERT G. ROTH, OF DRAKE, NORTH DAKOTA.

INTERNAL-COMBUSTION ENGINE.

1,221,094.

Specification of Letters Patent.

Patented Apr. 3, 1917.

Application filed January 2, 1913. Serial No. 739,769.

To all whom it may concern:

Be it known that I, ALBERT G. ROTH, a citizen of the United States, residing at Drake, in the county of McHenry and State of North Dakota, have invented new and useful Improvements in Internal-Combustion Engines, of which the following is a specification.

My present invention relates to internal combustion engines of the multiple cylinder type, including a plurality of drive shafts.

The principal object of my invention is to provide an engine of the character described in which the cylinders have a common combustion chamber, the inlet and exhaust ports of which are controlled by movement of one of the engine crank shafts, so that the pistons move in unison for the intake, compression, power and exhaust strokes. With this end in view, I so dispose the cylinders that the axes of their bores converge toward the combustion chamber, and thus attain a further object,—to condense the engine to a minimum magnitude consistent with other desirable features to be hereinafter more specifically set forth.

In the drawings, forming a part of this specification:

Figure 1 is a central vertical sectional view through a multiple cylinder engine constructed according to my invention.

Fig. 2 is a sectional view on the line 2—2 of Fig. 1.

Fig. 3 is a fragmentary view showing mechanism for imparting movement of the engine drive shaft to valve actuating mechanism, at a positive velocity ratio.

In the drawings, where similar characters refer to similar parts, 4 designates a base having bearings for crank shafts 5, disposed in parallelism and preferably providing a crank case 6 within which the crank pins 7 of shafts 5 make their phases of rotation.

Mounted upon base 4 are jacketed cylinders 8 the bores of which open into a common combustion chamber 9, with their axes converging toward said chamber. Intermediate the cylinders 8 I provide a wall 10 having ports 11 and 12, for intake and exhaust, respectively, of the engine, as will be hereinafter described.

The cylinders 8 contain reciprocable pistons 13, which are preferably of the trunk type, and have connecting rods 14 pivoted therein the said connecting rods 14 are in

turn connected to the crank shafts 5 through the medium of the crank pins 7.

The spark plug of the engine is designated by 15, and is preferably disposed equidistant from each cylinder 8 at the head of combustion chamber 9. It is to be noted that the pressure faces of pistons 13 are in planes at right angles to the axis of symmetry common to both cylinders and each is not at a right angle to the axis of its respective cylinder.

The ports 11 and 12 are controlled by valves 16 and 17, respectively, carried by reciprocable rods 18 and 19 respectively. These rods are carried by bearings 20 and 21 and extend intermediate the cylinders 8, longitudinally thereof. These valves are normally held closed by yieldable means, such as springs 22 confined between bearings 20 and abutments 23 on the valve rods.

Disposed with its axis substantially parallel to the axis of shaft 5 is a cam shaft 24, carried by bearings 25 of base 4. Two cams 26 and 27 are carried by shaft 24 for coaction with valve rods 18 and 19, respectively, as through adjustable roller bearings 28 and 29, respectively, whereby the valves may be adjusted to operate as desired, and according to the various strokes of the engine piston.

Shaft 24 may be driven through mechanism 30, at a positive velocity ratio from one of the shafts 5, this mechanism 30 preferably comprising conesring gears 31, 32 and 33, adapted to provide a velocity ratio of 2 between shafts 5 and 24, in the example shown.

The operation of the engine is as follows:

As disclosed in Figs. 1 and 2 of the drawing, the pistons 13 of the engine are at the start of the intake stroke, and port 11 is opened, by means of the raising of valve 16 through cam 26. As the pistons complete the intake stroke, the roller bearing 28 drops from the throw side of cam 26 and port 11 is closed responsive to action of spring 22 associated with the rod 18 of valve 16. The pistons then pass successively through the compression and power strokes, and when moving toward combustion chamber 9 to complete the exhaust stroke the valve 17 is raised by the cam 27 and the exhaust port opened for egress of the waste products of combustion.

It is to be noted that the intake and ex-

haust ports are equidistant from both cylinders, and hence the charge is uniformly distributed within the combustion chamber. Also, the spark plug 15 is so disposed as to ignite the charge at a point equidistant from both cylinders, hence, the pistons have imparted thereto substantially uniform movement by the expanding gases resulting from the explosion.

10 Changes in details may be made without departing from the spirit or scope of my invention; but,

I claim:—

15 In an internal combustion engine, in combination a pair of cylinders having a common combustion chamber and inclined therefrom in opposite directions, the inner opposed walls of said cylinders having a common vertex, crank shaft casings spaced
20 upon a common base and respectively sup-

porting said cylinders, pistons operable within said cylinders and adapted to have their pressure faces in longitudinal alignment with one another at the completion of an inward stroke and substantially flushed 25 with said vertex, crank shafts operably connected to said pistons, valves mounted at the said vertex of the inner opposed walls of the cylinders and provided with valve stems depending between said cylinders into 30 the space between said crank shaft casings, a cam shaft journaled horizontally between said casings and engaging said valve stems and means for transmitting motion from said crank shaft to said cam shaft. 35

ALBERT G. ROTH.
